BEVERAGE STIRRER OR THE LIKE

Mortimore H. Saffran, Hamden, Conn., assignor to Stelray Products, Inc., Shelton, Conn., a corporation of Connecticut

Filed July 6, 1967, Ser. No. 7,721

Term of patent 14 years

(Cl. D44—29)

FIG. 1

The essential features of my design reside in the portions shown in full line.

I claim:

The ornamental design for a beverage stirrer or the like, as shown and described.
